ATTORNEY.

UNITED STATES PATENT OFFICE.

JOHN WOLF, OF TOPEKA, KANSAS.

LOCK.

1,311,258.

Specification of Letters Patent. Patented July 29, 1919.

Application filed May 12, 1919. Serial No. 296,375.

To all whom it may concern:

Be it known that I, JOHN WOLF, a citizen of the United States, residing at Topeka, in the county of Shawnee and State of Kansas, have invented certain new and useful Improvements in Locks, of which the following is a full, clear, and exact description, reference being had to the accompanying drawings, forming a part hereof.

10 The present invention is directed to improvements in lid fasteners, and particularly to trunk-lid fasteners usually employed in conjunction with the lock by which the lid is locked to the body of the trunk. The 15 object of the invention is to construct a fastener that is simple, durable, effective, cheap, and quickly manipulated, and one possessing further and other advantages better apparent from the following detailed description 20 in connection with the accompanying drawings in which—

Figure 1 represents a top plan of a wardrobe trunk showing my invention applied thereto; Fig. 2 is a front elevation of the 25 upper end of the trunk with my fastener in place; Fig. 3 is a top plan of the fastener, part of the upper wall being broken away; Fig. 4 is a middle longitudinal section on the line 4—4 of Fig. 3 with trunk and lid 30 walls in section; Fig. 5 is a bottom plan of the fastener showing the operating parts exposed; Fig. 6 is a transverse section on the line 6—6 of Fig. 4; Fig. 7 is a detached perspective of the locking bolt; and Fig. 8 is a 35 side elevation of the fastener.

Referring to the drawings, T, represents the main section of the trunk, T' the horizontally swinging vertical section hinged thereto, L, the lid hinged to the section T', 40 and A the lock by which the lid is locked to the section T, the usual valance b being secured to the section T and lid L as well understood in the art, the sections parting along the seam a covered by the valance. 45 The fastener comprises a keeper 1 in the form of an oblong shell or casing, preferably secured by means of two prongs or nails 2, 2, formed integrally with the longitudinal wall of the shell and driven through the 50 plate or fitting 3 and valance b secured to the wall of the lid L as shown. The keeper 1 when the lid L is closed forms a continuation or extension of the shell or casing 4 secured to the trunk section T, said casing being open at one end and mounted on the

plate or fitting 5 to which and to the trunk section T the same is secured by means of the teeth or prongs 6 disposed on the edges of the end and side walls of the casing, said teeth being driven through the fitting well 60 into the wall of the trunk (Fig. 4). When the lid L is closed the shells 1 and 4 constitute in effect a single casing for the inner operating parts of the fastener. Formed at intermediate points along the edges of the side walls of the casing 4 are U-shaped depressions d, said depressions serving as bearings for the trunnions 7, 7, of an oscillating frame or yoke 8 spanning the casings 1 and 4, the outer cross member of the yoke being 65 formed with a finger hold or lip 9 by which the same may be manipulated. The inner ends of the trunnions are formed with arms or offsets 10 which are in turn connected by a cam member 11, the general appearance of 70 the parts 7, 10, 11, resembling a double crank shaft, the parts 10 corresponding to the crank arms and the part 11 to the crank pin. The cross-section of the cam is substantially 75 as shown in Fig. 4, the same having a decided nose or protuberance n at the point of maximum sweep of the cam, the purpose of which will presently appear.

Mounted slidably and reciprocably in the casing 4 is the bolt 12 the sides of which are 80 provided with guides or runners 13, 13, extending a suitable distance beyond the rear edge of the bolt, one of the runners terminating at the rear end in a foot 14 of the same width as the runner, the corresponding 85 end of the opposite runner terminating in a foot 14' extending laterally and inwardly and forming an offset or shoulder t with the inner face of the runner. The inner edge of the bolt 12 is formed with a central lug 90 15, the feet 14, 14', being spaced sufficiently from the free end of the lug 15 to accommodate between them the trunnions 7, 7, with their offsets 10, 10, and connecting cam 11. In other words, when the trunnions 7 95 of the yoke 8 are deposited in their depressions or bearings d, and the bolt 12 with its runners is properly placed in the casing 4, the yoke is free to oscillate about the common axis of the trunnions 7, 7, the cam 11 100 engaging the lug 15 and forcing the bolt outwardly or into the keeper 1 with a downward or forward throw or oscillation of the yoke; and engaging the shoulder t of the foot 14' and forcing the bolt inwardly or 105 110

out of the keeper with a complete upward or rearward throw of the yoke. In Fig. 4 the yoke is shown dotted at the middle of its stroke (upward or downward). Formed 5 in the roof of the casing 4 is a slight depression *h* in which is secured one end of a flexed spring 16, the free end of which constantly bears and rides over the surface of the cam 11, the purpose of the spring being 10 to hold the yoke 8 locked when it reaches the end of either of its strokes or throws. Thus, in Fig. 4 the spring bears against the concave side of the cam to one side of the rotation axis of the trunnions 7, 7, the pressure 15 exerted by the spring on the cam holding the yoke to its locking position. When the yoke is swung one hundred and eighty (180) degrees to the left the spring will obviously bear against the diametrically opposite face of the cam and hold the yoke to its unlocking or releasing position, the depression *h* accommodating the spring when the nose *n* of the cam forces it against the roof of the casing 4. The nose *n* may 20 be considered as the most active part of the cam, the same rubbing against the end of the lug 15 of the bolt with a forward or locking stroke of the yoke thereby driving the bolt across the seam *i* between the plates 25 5 and 3 well into or under the keeper 1, the said nose rubbing against the shoulder *t* of the foot 14' of the runner 13 with a rearward or releasing stroke of the yoke, and thereby forcing the bolt away from the 30 keeper 1 and permitting the lid *L* to be swung open after the lock *A* is unlocked. The casing 4 is preferably provided with a cross-strip 17 projecting inwardly along the free edge of the roof thereof, said strip being 35 of a length to freely admit the runners 13 between the ends of the strip and the inner faces of the side walls of the casing, but being of sufficient length to foul the shoulder *t* of the foot 14', thereby preventing 40 the bolt from dropping out of the casing with an assembling of the parts. This strip 17 is however not indispensable. The fixed end of the spring 16 terminates at this strip. The feet 14, 14', obviously serve to 45 guide the bolt, bearing as they do on the plate 5 to which the casing 4 is secured, said feet being disposed at right angles to the runners 13, that is to say, at right angles to the plane of movement of the bolt. Obviously, I may change the construction in 50 many particulars without departing from the nature or spirit of the invention. Again, the valance *b* herein shown as secured to the trunk section *T* may be shifted 55 to the trunk section *T'*. Likewise may the positions of the members 4 and 1 of the fastener be reversed, that is to say the keeper 1 may be on the trunk section *T* and the casing 4 may be placed on the lid *L*. The 60 fastener is of course not limited in its ap-

plication to trunks or trunk lids but may be used in any art wherever the same is applicable.

Having described my invention what I claim is:

1. In a fastener of the character described, a casing, a sliding bolt in the casing, an oscillating member operable from a point outside the casing, a cam on the member disposed about the axis of oscillation of the member, and suitable formations on the bolt 75 engaging the cam on opposite sides of said axis, whereby the bolt may be actuated in either direction depending on the direction of throw of the oscillating member. 80

2. In a lid fastener of the character described, a casing open at one end, a keeper coöoperating therewith and forming an extension thereof with a bringing together of the parts, an oscillating yoke spanning the 85 casing and provided with a pair of trunnions mounted rotatably in the side walls of the casing, a central cam connected to the trunnions and offset from the axis of the trunnions, a sliding bolt in the casing, guide 90 members or runners carried by the bolt and extending beyond the inner edge of the same, a lug projecting inwardly from said edge, feet projecting at an angle from the inner free ends of the runners, one of the feet being formed with an offset facing the opposite runner, said feet being spaced from the lug sufficiently to admit the cam of the yoke between them and the lug, the cam being provided with a formation bearing against the 95 lug of the bolt with a sweep of the yoke in one direction to drive the bolt toward the keeper, and bearing against the offset aforesaid to drive the bolt away from the keeper with a sweep of the yoke in the opposite direction. 100

3. In a lid fastener of the character described, a bolt-actuating yoke comprising an open frame having trunnions at one end thereof directed inwardly toward the axis 110 of the yoke, offsets or arms leading from the trunnions at an angle to the axis of the trunnions, a cam connecting the sweep ends of the offsets, and a sliding bolt having formations coöperating with the cam for driving the 115 bolt first in one direction and then the other depending on the direction of throw of the yoke.

4. In a lid fastener of the character described, a bolt provided with side runners 120 extending beyond the rear edge of the bolt, feet at the free ends of the runners projecting at right angles to the plane of movement of the bolt, one of the feet being formed with an offset leading from the inner face of the runner, and a lug projecting from the inner edge of the bolt and spaced from a transverse plane connecting the inner faces of the feet. 125

5. In a fastener of the character de- 130

scribed, an oscillating yoke provided with a cam, a flexed spring bearing against the cam, a fixed support for the spring, and a sliding bolt actuated by the cam and engaging the cam at points removed from the spring.

In testimony whereof I affix my signature, in presence of two witnesses.

JOHN WOLF.
